UNITED STATES PATENT OFFICE

149,383

DESIGN FOR A WHEELED TOY TORTOISE

Harry Sebel, London, England

Application May 16, 1946, Serial No. 129,759

Term of patent 14 years

(Cl. D34—15)

To all whom it may concern:

Be it known that I, Harry Sebel, a subject of the King of Great Britain, residing at London, England, have invented a new, original, and ornamental Design for a Wheeled Toy Tortoise, of which the following is a specification, reference being had to the accompanying drawing, forming part thereof.

Fig. 1 is a front perspective view of a wheeled toy tortoise showing my new design; and

Fig. 2 is a rear perspective view of the toy tortoise referred to in Fig. 1.

I claim:

The ornamental design for a wheeled toy tortoise, as shown.

HARRY SEBEL.
